CLOTHES-DRYING RACK

James Gilbert Rothrock, Everett, Wash.

Application October 25, 1945, Serial No. 624,393

2 Claims. (Cl. 211—100)

1

This invention relates to a clothes drying rack and an object of this invention is to provide a clothes drying rack comprising a cabinet of neat and ornamental appearance adapted to be hung on a wall and that will occupy little space when not in use, said cabinet carrying a relatively large number of clothes drying bars that are housed in the cabinet when not in use and that may be extended horizontally to provide a relatively great total bar length for the hanging of clothes to be dried.

Another object is to provide a clothes drying rack having novel and efficient means for supporting a plurality of clothes bars in an extended or substantially horizontal position, said means permitting the bars to be quickly and easily moved from a folded to an extended position or vice versa.

Other objects are to provide a clothes drying rack of strong, simple, efficient and compact construction that is not expensive to manufacture, that is neat and ornamental in appearance, that is easy to put up and take down, that hangs close to a wall and does not obstruct room space when not in use, and one in which the clothes bars are almost completely housed when not in use and are readily movable between a folded and an extended position or vice versa.

Another object is to provide a clothes drying rack of a design that is equally well adapted to either wood or metal construction and one that can be readily constructed in different sizes to provide for different total clothes bar length.

In the drawings

Figure 1 is a front elevation of a wooden clothes drying rack constructed in accordance with my invention, the clothes bars being omitted.

Fig. 2 is a plan view of the same showing a plurality of clothes bars in an extended or clothes receiving position.

Fig. 3 is a sectional view taken substantially on broken line 3—3 of Fig. 1 showing, by full lines, a fragment of a clothes bar in an extended or horizontal position and showing, by dot and dash lines, a clothes bar in a folded or upright position.

Fig. 4 is a detached perspective view, with parts broken away, of a clothes bar used in connection with my invention.

Fig. 5 is a view in front elevation of a sheet metal clothes rack constructed in accordance with this invention, the clothes bars being omitted.

Fig. 6 is a vertical sectional view, taken substantially on line 6—6 of Fig. 5, of a metal clothes drying rack constructed in accordance with this invention, showing by full lines a fragment of a clothes bar in an extended position and by dot and dash lines a clothes bar in a folded position.

Fig. 7 is a view in cross section taken substantially on broken line 7—7 of Fig. 5.

Fig. 8 is a fragmentary perspective view of a

2

tubular clothes bar used in the rack shown in Figs. 5 and 6.

Fig. 9 is a front elevation of a modified form of the invention, with the clothes bars omitted.

Figs. 10 and 11 are sectional views taken on broken lines 10—10 and 11—11 respectively of Fig. 9.

Like reference numerals designate like parts throughout the several views.

Figs. 1 to 4 show a wooden clothes rack. This clothes rack comprises a cabinet formed of a rear wall 12, a front wall 13, side walls 14 and a bottom wall 15. This cabinet, as viewed from the front or back, is preferably of somewhat triangular shape, is wider at the top and is squarely cut off or truncated at the bottom.

The front wall 13 is provided with a reinforcing strip 18 that extends across the top edge thereof and cooperates with the front wall in forming a fulcrum member on which the bars 17 rest when they are in extended position.

The back wall 12 extends above the front wall 13 and preferably has a hand hold slot 19 and two keyhole shaped slots 20 therein. The keyhole slots 20 are adapted to receive nails or screws that protrude outwardly from a wall to suspend the clothes rack from the wall.

Horizontal clothes bar holding means is secured to the front side of the back member 12 a short distance above the top edge of the front member 13. The clothes bar holding means herein shown comprises a cross piece 21 of substantially square cross section and a thinner and wider cross piece 22 that extends below the cross piece 21 and has notches 23 extending from its bottom edge upwardly. The cross piece 21 is positioned against the back 12 and the cross piece 22 is positioned against the front face of the cross piece 21 and said two cross pieces are rigidly secured to each other and to the back 12 of the cabinet.

All parts of the cabinet are secured together by nails or screws or glue or by any desired combination of nails, screws and glue.

The clothes bars 17 may be of rectangular cross section, Fig. 4, and each side of each clothes bar 17 is transversely grooved near the inner end of the bar to provide a narrower neck portion 24 adapted to fit within one of the notches 23 and to leave a head 25 at the extreme inner end of the bar. The head 25 prevents the bar from being pulled forwardly out of a slot 23 in which the neck portion 24 is disposed.

When the clothes bars 17 are not in use they preferably are stored in an upright position in the receptacle 16, as indicated by dot and dash lines in Fig. 3. When these bars 17 are to be used to hang clothes on they may be drawn upwardly and outwardly from the receptacle 16 and the narrower neck portion 24 near the inner

end of each bar 17 engaged within one of the notches 23. This will support each bar 17 in a substantially horizontal position as shown by full lines in Fig. 3.

The neck portions 24 of the bars 17 are narrower than the notches 23 and longer than the thickness of the piece 22. This makes it possible to position the bars 17 at an angle other than perpendicular to the cross piece 22. Thus the bars 17 can be spread out in fan shape, as shown in Fig. 2. Also these bars 17 can be entirely removed from the cabinet.

The cabinet is of symmetrical design and may, if desired, be artistically decorated to further improve its appearance. Preferably molding strips 27 are provided on the front of this cabinet adjacent the two sides and bottom thereof.

Figs. 5, 6, 7, and 8 show a clothes drying rack of this type which is varied in design to adapt it to be constructed out of sheet metal, such as aluminum. The cabinet of this rack comprises a back wall 30, a front wall 31, side walls 32 and a bottom wall 33. The top edge of the front wall 31 has an outwardly curved lip 34 to provide transverse strength and serve as a fulcrum for bars 35 on which clothes may be hung.

The side walls 32 and bottom wall 33 are preferably formed by bending over portions of the edges of one of the other walls such as the front wall. This cabinet may be assembled by spot welding or riveting tabs 36 of the side walls 32 and bottom 33 to the back wall 30. The means with which the inner end portions of the bars 35 may be detachably engaged is a piece of sheet metal bent to channel shaped cross section. The front flange 37 of this channel shaped cross bar 37' has notches 38 extending from its bottom edge upwardly. The rear flange 39 of said cross bar is welded or otherwise fixedly secured to the rear wall 30.

Preferably the bars 35 are of tubular cross section and each bar has its opposite side portions flattened near its inner end to provide a narrower neck portion 40 adapted to fit within one of the notches 38 and a head portion 41 which can not be pulled through a notch 38.

The clothes rack shown in Figs. 5, 6, 7 and 8 functions in substantially the same manner as the clothes rack shown in Figs. 1 to 4.

Figs. 9, 10 and 11 show a clothes rack of modified form adapted for the use of bars 17 of the form shown in Figs. 2, 3 and 4 or bars 35 of the form shown in Figs. 6 and 8. The clothes rack shown in Figs. 9, 10 and 11 comprises a bar holding member 42 of any desired length having a centrally positioned downwardly extending receptacle 43 for receiving and holding the clothes bars when they are not in use.

The bar holding member 42 may be formed of a single piece of sheet metal bent to provide fulcrum member 44 on which the bars may rest and having a hook shaped portion 45 provided with notches 46 in which the neck portions of the bars engage. The receptacle 43 is preferably fixedly secured to the bar holding member 42. The bar holding member may be of relatively great length to hold a large number of bars.

In the use of the device shown in Figs. 9, 10 and 11 the bars that are to be supported in notches 46 to either side of the receptacle 43 can be entirely removed from the holder in moving them between an extended and a folded position

or they can be elevated into a substantially vertical position and slidably moved along the bar holding member 43.

The foregoing description and accompanying drawings clearly disclose preferred embodiments of this invention but it will be understood that changes in the invention may be made within the scope and spirit of the following claims.

I claim:

- 10 1. In a clothes drying rack, a relatively deep receptacle of narrow thickness from front to rear and having substantially parallel front and rear walls and having a bottom wall; a horizontal fulcrum member carried by the upper edge portion 15 of the front wall of said receptacle; horizontal clothes bar holding means carried by the rear wall of said receptacle and extending toward said fulcrum member above the level of said fulcrum member and having downwardly opening clothes 20 bar positioning notches; and clothes bars each having a neck portion of narrower width than the bar near the inner end of the bar and a terminal head portion wider than said neck portion inwardly of said neck portion, whereby when said 25 neck portions are positioned in said notches said bars will be held against endwise movement and will be supported in extended positions by said clothes bar holding means and said fulcrum member, said bars being readily movable into upright 30 positions with the inner end portions of the bars resting on the bottom wall of the cabinet and the major portions of the bars disposed within the cabinet and the outer end portions of the bars extending above the clothes bar holding 35 means.
2. In a clothes drying rack, a relatively deep clothes bar receptacle of narrow thickness having a front wall and a rear wall adapted to be positioned against a wall; clothes bars adapted to 40 be disposed in said receptacle, each clothes bar having a neck portion of narrower width than the bar near its inner end and having a terminal head portion wider than said neck; a horizontal clothes bar fulcrum member carried by the upper 45 edge of the front wall of said receptacle; a clothes bar holding member of substantially inverted hook shape in cross section supported from the rear wall of said receptacle, said clothes bar holding member having a flat outer portion spaced 50 between said rear wall and said fulcrum member, the bottom edge of said flat outer portion being approximately flush with the top edge of said fulcrum member; and notches of narrower width than said clothes bars in the flat outer portion of 55 said clothes bar holding member extending from the bottom edge thereof upwardly adapted to releasably receive the narrower neck portions of said bars.

JAMES GILBERT ROTHROCK.
